UNITED STATES PATENT OFFICE.

WILLIAM L. DE GRACE, OF NORTH SYDNEY, CANADA, ASSIGNOR OF ONE-HALF TO WILLIAM PURVES, OF SAME PLACE.

THILL-COUPLING.

SPECIFICATION forming part of Letters Patent No. 563,846, dated July 14, 1896.

Application filed November 18, 1895. Serial No. 569,314. (No model.)

To all whom it may concern:

Be it known that I, WILLIAM L. DE GRACE,
a citizen of Canada, residing at North Sydney,
in the county of Cape Breton and Province of
5 Nova Scotia, Canada, have invented certain
new and useful Improvements in Thill-Cou-
plings; and I do declare the following to be a
full, clear, and exact description of the inven-
tion, such as will enable others skilled in the
10 art to which it appertains to make and use the
same.

This invention relates to improvements in
thill-couplings, and its novelty and many ad-
vantages will appear from the following de-
scription and claims when taken in connec-
tion with the annexed drawings, in which—

Figure 1 is a cross-sectional view of an axle, showing my improvements in longitudinal section and attached thereto with a thill 20 partly broken away. Fig. 2 is a side view of the improvements, showing the same in the act of being coupled with parts broken away. Fig. 3 is a sectional view taken in the plane indicated by the dotted line x x on Fig. 1; 25 and Fig. 4 is a broken perspective view of the improvements, showing the same uncoupled.

Referring by letter to said drawings, A indicates a clip which is shackled to an axle B in the usual manner. This clip projects forwardly of the axle, as shown, and has its forward end terminating in an upwardly-curved branch *a*. On the inner or upper side of this curved branch, and extending into the horizontal portion of the clip, is a groove or recess *b*. This groove, which opens at the free end of the curved portion *a*, preferably increases in depth at an intermediate point in its length and tapers toward its inner end, as shown at *c*.

40 C indicates the thill-iron. This iron, which
is secured to the thill *d* in the usual manner,
has its rear end terminating in a downwardly-
curved portion or hook *e*, and this hook or
curved portion is provided centrally with a
45 depending curved portion or cam *f*, which is
designed to enter the groove or recess *b* of the
clip *A*. By having this portion *f* of a cam
shape it will be seen that the thill must be
raised to a perpendicular position, or nearly
50 so, before such cam can enter the groove or
recess *b* of the clip, and by letting the thill

down to a horizontal position, or approximately so, the said cam will move in said groove or recess, so that there will be no liability for lateral displacement. In order to 55 prevent vertical displacement of the parts, or rearward movement of the thill, I provide a plate D. This plate is adjustably secured to the under side of the thill-iron C by means of bolts E and F and nuts or other suitable 60 fastening devices.

The forward portion of the clip A is rounded on its under side, as shown at *g*, and the contiguous side of the plate D has a curvature corresponding with that of the outer side of the curved portion *a* of the clip, and this plate D is secured to the thill-iron at such a distance with respect to the curved or hook portion *e* of the thill-iron as to permit the introduction of the hooked or curved end of the clip between the same. By the employment of this plate D it will be seen that the thills, while in a horizontal or approximately horizontal position, will be prevented from rising or moving rearwardly, while the cam projection coöperating with the groove or recess in the clip-plate will absolutely prevent any lateral movement of the parts. While the foregoing is true, it will be observed that when the thills are raised to a vertical or approximately vertical position and then lifted the thill-iron C and plate D will be disengaged from the clip A. As in practice the frictional parts become worn, which would result in a loose joint of the coupling and consequent rattling of the same, I provide the plate D with slots *h* instead of holes, so that as the parts become worn the plate may be set closer to the hook or curved portion carrying the cam projection, and thereby tighten the connection of the parts. It will be observed that while the bolt *e* goes straight through the thill-iron and plate D the bolt F passes through rearwardly oblique, the slots being formed in this oblique or inclined manner, so that the bolt may be more effectively operated in tightening the joint or connection.

While I have shown and described the clip as having the groove or recess, and the thill-iron as having the cam projection, yet it is obvious that this arrangement may be reversed by placing the groove or recess in the thill-iron 100

and the projection in the clip, and I am also aware that other modifications may be made in the construction of the parts without departing from the spirit of my invention.

5 Having described my invention, what I claim is—

1. In a thill-coupling, the combination of the clip having its forward end hooked or curved upwardly and provided in its inner or upper side with a central longitudinal groove, a thill-iron having its rear end provided with a hook or downwardly-curved portion and having a projection thereon adapted to enter and move in the groove or recess in the clip, and the plate connected to the thill-iron and having the curved portion resting against and conforming in curvature to the outer side of the curved portion of the clip, substantially as and for the purpose set forth.

2. The thill-iron having its rear end provided with a downwardly-curved portion or hook and a cam projection on the forward side and end of said curved portion or hook, in combination with the clip having the upwardly-curved portion or hook and a recess 25 in the inner or upper side of said hook to receive the cam projection, and the plate having the slots as described and also having a curvature corresponding to the outer surface of the curved portion or hook of the clip, and the bolts for adjustably securing the plate to the thill-iron, substantially as specified.

In testimony whereof I affix my signature in presence of two witnesses.

WM. L. DE GRACE.
